UNITED STATES PATENT OFFICE

PAUL LUX, OF WATERBURY, CONNECTICUT, ASSIGNOR TO LUX CLOCK MANUFACTURING COMPANY, INC., OF WATERBURY, CONNECTICUT, A CORPORATION OF CONNECTICUT

DESIGN FOR A COMBINED CASING FOR AN ALARM CLOCK AND DIAL THEREFOR

Application filed May 6, 1929. Serial No. 31,121. Term of patent 3½ years.

To all whom it may concern:

Be it known that I, PAUL LUX, a citizen of the United States, residing at Waterbury, county of New Haven, and State of Connecticut, have invented a new, original, and ornamental Design for a Combined Casing for an Alarm Clock and Dial Therefor, of which the following is a specification, reference being had to the accompanying drawing forming part thereof.

Fig. 1 is a front elevational view of a com-

bined casing for an alarm clock and dial therefor showing my new design.

Fig. 2 is a side elevation of the same.

I claim:

The ornamental design for a combined casing for an alarm clock and dial therefor as shown.

In testimony whereof, I have affixed my signature to this specification.

PAUL LUX.
